ELECTRICAL CONNECTOR

Gordon W. Dean, Alhambra, Calif., assignor to Cannon Electric Company, Los Angeles, Calif., a corporation of California

Filed Feb. 10, 1959, Ser. No. 792,287

6 Claims. (Cl. 339—49)

This invention relates to electrical connectors and to contact elements for electrical connectors.

It is an object of this invention to provide an electrical connector composed of two connector members having contact elements therein which are adapted to be connected to the ends of conductor wires respectively of a cable, the connector members being mateable and being generally similar to each other in structure and design whereby either of the connector members may serve as a receptacle or as a plug.

Another object of this invention is to provide an improved electrical contact element adapted to be mounted in a connector member and adapted to provide an effective and efficient electrical connection with a contact element of another connector member, the contact elements being generally similar to each other in construction and design.

A further object is to provide a contact element of the above mentioned character and adapted to be connected to the end of a conductor wire and then inserted, with the wire attached thereto, into the body of a connector member, the contact element having means for preventing being withdrawn from the connector member.

A general object of this invention is to provide electrical connector members and contact elements therefor of the above mentioned character which are relatively simple and easy to manufacture, are rugged in construction and are reliable in operation.

The invention is especially advantageous when embodied in an electrical connector having a plurality of contact elements for making a multiplicity of electrical circuits. The connector members of this invention are adapted to be formed from a plurality of structural units permitting any desired number of contact elements to be assembled easily for constituting a connector member.

Further objects and advantages of the invention will appear during the following part of this specification wherein the details of construction and mode of operation of a preferred embodiment are described with reference to the accompanying drawing in which:

FIG. 1 is a cross section through an electrical connector of this invention and showing the two connector members thereof separated;

FIG. 2 is a cross section through the connector taken along the same plane for the section of FIG. 1, but showing the two connector members thereof joined;

FIG. 3 is a cross section through the electrical connector taken along line 3—3 of FIG. 2;

FIG. 4 is a plan view of an electrical contact element of this invention;

FIG. 5 is a longitudinal section through the contact element taken along line 5—5 of FIG. 4; and

FIG. 6 is a perspective view of the contact element.

Referring to the drawing in greater detail, there is shown an electrical connector of this invention comprising two connector members which are designated, generally, by reference numerals 10 and 11, respectively. The two connector members of the illustrated embodiment are substantially identical to each other in their details of construction and are adapted to be interengaged, as shown in FIG. 2 of the drawing, for interconnecting the contact elements or terminals 12 and 13 of connector member 10 with contact elements or terminals 14 and 15 of connector member 11, respectively.

2

Each of the contact elements is adapted to be connected (as will be explained more fully hereinafter) to the ends of conductors 16, respectively, whereby the electrical connector serves to join the conductors of one connector member to the conductors, respectively, of the other connector member.

Each connector member comprises a body or block 19 formed of non-conducting material. A synthetic polymer, e.g. nylon, is a preferred material from which to form the block. The block 19 is substantially cylindrical in form and rectangular in cross section, it having a forward end surface 20, a rearward end surface 21, and side surfaces 22, 23, 24, and 25.

The illustrated block constitutes an assembly of four strips of non-conducting material, these strips for block 19 of connector member 11 being a strip 26 which appears as a bottom strip in FIG. 1, a strip 27 upon the bottom strip, a strip 28 upon the strip 27, and a top strip 29. The strips 27 and 28 are identical to each other in the structural details thereof.

The body or block of the connector member 10 is likewise composed of four strips, these being designated by reference numerals to correspond with the reference numerals which designate the respective strips of the block 19 of connector member 11. The reference numerals for the several strips of the block of connector member 10 have a prime (') associated therewith to distinguish the component parts of the connector member 10 from the corresponding parts of connector member 11. It will be noted that the strip 26' of connector member 10 appears in the upper portion of FIG. 1 whereas the corresponding strip 26 of the connector member 11 appears as a bottom strip when viewed as in FIG. 1. In like manner the other strips which form the block of member 10 appear as turned upside-down with respect to their corresponding strips in the block of connector member 11. The configuration of each block is such that the block will mate with another block when turned on its axis 180° with respect to the other so that side surface 23', for example, of the block of member 10 will be aligned with side surface 22 of the block 19 of connector member 11 upon interengagement of the connector members.

Referring to FIGS. 4, 5 and 6 of the drawing, a contact element or terminal 14 is shown as the same may be formed from an elongate flat strip of metal having end edges 32 and 33. For convenience of reference herein, the terminal strip is described as comprising a contact-engaging front end portion 34 terminating at end edge 32 of the terminal strip, a conductor-connecting rear end portion 35 terminating at end edge 33 of the terminal strip, and a middle portion 36 between said end portions.

The conductor-connecting end portion 35 of the illustrated embodiment is formed as by bending the side edges of the terminal strip toward each other to provide an endwardmost disposed tubular portion or sleeve 37 which is crimped circumjacent the outside surface of a jacket or coating 38 of the conductor 16. The wire core of the conductor 16 is designated by reference numeral 39. The terminal strip is cut as along slits 40 to define an end of a tubular portion 41 of smaller diameter and which is crimped circumjacent the end of the wire 39 of the conductor thus to provide a secure electrical connection between the terminal strip and the conductor. It will be understood, of course, that other conventional forms for the conductor-connecting end portion of the terminal strip may be employed, such as, for example, a solder cup construction.

It is an important feature of this invention that the contact terminals are adapted to be connected to the ends of the conductors and then inserted into the blocks of the connector members where they will remain against

being withdrawn. For that purpose the middle portion 36 of the terminal strip has a spring retainer finger 43 struck from it leaving an opening 44 in the metal strip. The spring finger extends longitudinally with respect to the terminal strip with that end 45 of the finger which is remote from the conductor-connecting end portion of the strip, being integral with the strip, while the other end 46 of the finger is free. Thus, the finger may be pressed toward or partially into its opening, as when the terminal strip is being inserted in the insulation block, and then the finger will spring outwardly, when free to do so, to the position thereof shown in FIG. 5, whereby the end 46 of the finger will engage a shoulder (hereinafter identified) on the inside of the block to prevent withdrawal of the terminal from the block.

The contact-engaging end portion 34 of the terminal strip is narrower than the middle portion 36 to define shoulders 48 which extend axially inwardly from side edges 49 of the middle portion. The shoulders 48 will engage complementary shoulders (hereinafter identified) on the inside of the block to limit the extent to which the terminal strip may be inserted in the block. There are two spaced apart and parallel slits 51 formed in the contact-engaging end portion of the terminal strip extending through end edge 32 to provide a middle finger 52 and two side fingers 53. The middle finger is bowed outwardly from the axis of the strip between its ends as by being bent at line 55 where it is integral with the metal strip, to incline outwardly from the axis of the strip to a transverse bend line 56 from which the finger inclines back in a flat contacting portion toward the axis of the strip. Proximate end edge 32, the middle finger is again bent outwardly along bend line 57 to provide an end or lip lead-in portion 58 which enables easy interengagement of the middle finger of one terminal strip with the middle finger of another terminal strip with which it is to be interengaged. The side fingers 53 are also bowed outwardly from the axis of the terminal strip, but in a direction opposite to the bow of the middle finger, i.e. as a terminal strip appears in FIG. 6, the side fingers are bent downwardly from bend line 55, thence upwardly at bend line 56 so as to incline forwardly and back toward the axis of the strip in flat contacting portions, and thence downwardly again at bend line 57 to provide end lead-in portions 58' which make for easier interengagement with corresponding side fingers of another terminal.

The manner in which the contact terminals of connector member 10 interengage or mate with respective contact terminals of connector member 11 appears best in FIG. 2. Referring in particular to the contact terminal 14 of connector member 11 and to the terminal 12 of the connector member 10, these being in alignment for interengagement and being inverted with respect to each other, it will be noted that the end lip 58 of the middle finger of terminal 14 will be inclined downwardly, whereas the end lip of the middle finger of terminal 12 will be inclined upwardly so that in being interengaged the middle finger of terminal 14 will slide under the middle finger of terminal 12, each flexing the other until the inside faces of the end lips engage respective inside faces of the slant portions of the fingers between bend lines 55 and 56. The fingers will thus close flush against each other. In like manner the side fingers of terminal 14 will first flex and then mate with respective side fingers of terminal 12 as the terminals are interengaged.

Referring again to the details of construction of block 19 and to the thin strips 26-29 from which the block is formed, the strips are shaped such that when assembled together, they will define a plurality of openings 61 extending through the block from end to end thereof to receive the contact terminals, respectively. The sectional views of FIGS. 1 and 2 show but two contact terminals, 14 and 15, for the connector member 11; however, the

illustrated block is constructed to accommodate three contact terminals in the plane or row of terminals 14 and 15, hereinafter referred to as row *a*. For the purpose of better illustrating the details of construction for the inside walls which define the block openings 61, a lowermost opening 61a3 of the row *a* for connector member 11 is shown without having a contact terminal positioned therein. Also, by referring to FIG. 3 of the drawing, it will be noted that the block 19 of the illustrated embodiment is adapted to receive a row or tier *b* of contact terminals disposed alongside row *a*, but again a block opening 61b1 of row *b* is shown as not having a terminal positioned therein.

The openings 61 for the contact terminals are provided by forming longitudinally extending grooves in the upper and lower surfaces of the plurality of thin strips from which the block is formed whereby a groove in the upwardly disposed surface of intermediate strip 28, for example, will be aligned with a groove formed in the under-surface of top strip 29 thereby to provide an opening 61a1 for the contact terminal 14. As the openings 61 are adapted to receive respective contact terminals after the terminals have been secured on the ends of the conductors, the block openings have oppositely disposed key-way portions 63 extending from rearward end face 21 of the block and terminating at rearwardly facing shoulders 64 for receiving the side marginal portions 49 of the middle portion 36 of a terminal. These key-way or slot portions 63 are just wide enough to accommodate the marginal portions 49 whereby the side walls of the key-ways serve to prevent a terminal from turning on its longitudinal axis. Also, the key-way slots 63 are deep enough only to allow the middle portion of a terminal to fit snugly between the slot bottoms whereby the side edges 49 of a terminal will hold the terminal against axial misalignment in its opening in the block. Shoulders 48 on the terminals abut against shoulders 64 of the block openings to prevent axial movement of a terminal in its opening in a direction toward the forward end 20 of the block.

The grooves which form the openings 61 are recessed or countersunk at 66 and 67 to accommodate the tubular portions 38 and 41, respectively, of a terminal. The illustrated embodiment is one in which its contact terminals are entirely contained within the insulation block. It is to be understood, of course, that it is not necessary that the conductor-connecting end portions of the terminals be contained entirely within the block, for in some installations such end portions may extend out beyond the rearward end surface 21 of the block.

At the inner end of the recess 66 for the undersurface of block strip 29, there is a land 68 extending to the inner end of a recessed portion 69. This structure appears best in the lower left-hand portion of FIG. 3 showing an opening 61b1 of connector member 10, the same being shown as not having a contact terminal positioned therein. That part of a block opening which is designated by reference numeral 61b1 is formed in the top surface of block strip 27, such top surface being identical with the undersurface of strip 29. As a contact terminal is being inserted in its block opening, the spring finger 43 on the terminal will be pressed, by sliding engagement against the land 68, into or toward opening 44. When next the shoulders 48 of the terminals reach the shoulders 64, the spring finger will be free to spring out into the recess 69 where its free end 46 will be disposed adjacent shoulder 70 which defines the bottom or inner end of the recess 69. Thus, upon a terminal being positioned in its opening as just described, the spring finger 43, by engagement with shoulder 70, will prevent withdrawal of the terminal from its block opening in a direction axially toward the rearward face 21 of the block.

Forwardly of the recess 69, block opening 61a1 in the undersurface of block strip 29 for terminal 14 (as does opening 61b1) continues as a recessed portion 72 of increased cross-sectional dimensions for accommodating

the conductor-connecting end portion 35 of a contact terminal. Each of the block strips has a plug or male portion 74 extending outwardly beyond the forward wall 20. Such outwardly extending portions 74 serve to shield the outer ends of the contact fingers of the terminals. The outer ends of the portions 74 are designated by reference numeral 75. A land 76 serves to separate a block opening 61'a'1 in the *a* row or tier of terminals from its adjacent block opening 61'b'1 in the *b* row of terminals.

The other half of the block opening 61'a1 for the terminal 14 is defined by a groove formed in the upper surface of intermediate strip 28 of the block, and the details of construction thereof appear best in the lower right-hand portion of FIG. 3 as opening 61b1. The groove 61b1 in strip 28 is generally similar to the groove 61'b'1 above described, but it does not have any recess formed therein corresponding to the recess 69. The two grooves for the block openings 61'a1 and 61b1 in the upper surface of block strip 28 are separated by a land 78 which terminates at bottom wall 79 of a forwardly disposed recess 80. The recess 80 extends between the two adjacent block openings of the *a* and *b* rows thus to provide a socket portion, constituted of the recess 80, for reception of a plug portion 74' in the forward end of strip 27'. The block portions 74 are narrower than the dimension between side walls 24 and 25 of the block 19 so as to be received within respective recesses 80.

From the above description it will be apparent that each block 19 is formed of a plurality of strips laid one upon the other, one surface for the intermediate strips 27 and 28 having grooves formed therein as above described for 61b1 and the other surface having grooves formed therein as above described for 61'b'1. For the endmost members 26 and 29 of the stack of strips one endmost strip member 29 has grooves formed therein as above described for 61'b'1, while the other endmost strip 26 has grooves formed therein as above described for 61b1. Thus, the top surface of the opening separating land 78 of intermediate strip 28, for example, will lie flush against opening separating land 76 of strip 29. Before the contact terminals are inserted into their respective block openings, the several block strips are made integral with each other in a stack as with a suitable solvent serving as an adhesive.

For some installations it may be desired to encase the blocks in a shell, e.g. shell 83 for the block of the connector member 11 and shell 84 for block 10. The shell 83 has an end flange 85 lapped over the outer surface 21 of the block and has a bead 86 which extends into a groove 87 formed in the outside surfaces of the strips 26 and 29, such end flange and bead serving to secure the shell around the block. Also the shell 83 may have an outwardly extending flange 88 at its forward end for mounting the connector member 11 in an opening 89 of a panel 90. For an installation employing the flange 88, the connector member 11 will serve as a receptacle and the connector member 10 will serve as a plug, it being understood, however, that the blocks may be used without shells and also as units with shells but without any structure which would distinguish one as a receptacle member and the other as a plug member.

It is contemplated further that the blocks 19 may be grouped together in a battery formation. Thus in FIG. 3 there is shown along one side of block 19 a corresponding block 92 and at its other side another corresponding block 93. For preventing axial movement of the blocks 19, 92 and 93, they are provided with tongue and groove structures as shown at 94. For an installation employing a plurality of blocks side by side, the shell 83 will preferably encase all of them to serve as a connector member having a large number of contact elements.

While the instant invention has been shown and described herein, in what is conceived to be the most practical and preferred embodiment, it is recognized that departures may be made therefrom within the scope of

the invention, which is therefore not to be limited to the details disclosed herein, but is to be accorded the full scope of the claims.

What I claim is:

- 5 1. A contact terminal for an electrical connector which comprises: an elongate generally flat contact element having front and rear portions; means on said rear portion for engaging an electrical conductor; said front portion including three forwardly extending, longitudinally directed spring fingers arranged side-by-side so that one of said fingers is a middle finger and the other two fingers are side fingers positioned adjacent opposite sides of the middle finger; each of said fingers having a rear portion extending outwardly from the plane of the element, and a flat contacting portion inclining forwardly and inwardly toward the said plane from said rear portion; whereby said fingers are interengageable in overlying position with respective fingers of a similarly constructed contact element, with said flat contacting finger portions of one contact element mating with respective opposed flat contacting finger portions of the other contact element, said flat contacting portion of the middle finger being inclined relative to said plane in a direction opposite to the direction of incline of the flat contacting portions of the side fingers relative to said plane.
- 10 2. A contact terminal for an electrical connector as defined in claim 1 which includes a lead-in portion at the forward tip of each finger, said lead-in portion inclining forwardly and outwardly of said plane from said flat contacting portion of the respective finger on the same side of the plane as said flat contacting portion of the respective finger.
- 15 3. A contact terminal for an electrical connector as defined in claim 2 wherein said elongate contact element comprises an elongate generally flat strip of metal, said three spring fingers being formed therein by a pair of spaced, longitudinally arranged slits extending through said front portion of the contact element.
- 20 4. An electrical connector member which comprises: a body of non-conducting material having an opening extending therethrough; an elongate generally flat contact element disposed in said opening, said contact element having front and rear portions; means on said rear portion for engaging an electrical conductor; said front portion including three forwardly extending, longitudinally directed spring fingers arranged side-by-side so that one of said fingers is a middle finger and the other two fingers are side fingers positioned adjacent opposite sides of the middle finger; each of said fingers having a rear portion extending outwardly from the plane of the element, and a flat contacting portion inclining forwardly and inwardly toward said plane from said rear portion; whereby said fingers are interengageable in overlying position with respective fingers of a similarly constructed contact element, with said flat contacting finger portions of one contact element mating with respective opposed flat contacting finger portions of the other contact element, said flat contacting portion of the middle finger being inclined relative to said plane in a direction opposite to the direction of incline of the flat contacting portion of the side fingers relative to said plane.
- 25 5. An electrical connector member as defined in claim 4 which includes a lead-in portion at the forward tip of each finger, said lead-in portion inclining forwardly and outwardly of said plane from said flat contacting portion of the respective finger on the same side of said plane as said flat contacting portion of the respective finger.
- 30 6. An electrical connector member as defined in claim 5 wherein said elongate contact element comprises an elongate generally flat strip of metal, said three spring fingers being formed therein by a pair of spaced, longitudinally arranged slits extending through said front portion of the contact element.
